Inventor,

George A. Carter,

UNITED STATES PATENT OFFICE.

GEORGE A. CARTER, OF DES MOINES, IOWA.

WINDMILL PUMP AND REGULATOR.

SPECIFICATION forming part of Letters Patent No. 392,852, dated November 13, 1883.

Application filed May 17, 1886. Serial No. 202,443. (No model.)

To all whom it may concern:

Be it known that I, GEORGE A. CARTER, a citizen of the United States, residing at Des Moines, in the county of Polk and State of Iowa, have invented certain new and useful Improvements in Windmill Pumps and Regulators; and I do hereby declare the following to be a full, clear, and exact description of the invention, such as will enable others skilled in the art to which it appertains to make and use the same.

My invention relates to an improvement in windmill pumps and regulators, and particularly to that class wherein, when the tank has been pumped full, a float and valve cut off the supply and cause the water to rise in a cylinder and raise a piston, which, acting on a weighted lever, furls the sails of the wind-wheel, and by other similar connections likewise unfurls the sails when the water in the tank falls below a certain level; and it consists in the combination, with the frame of a force-pump, of the device for furling and unfurling the sails, to the end that it may be a complete adjustable article when it leaves the factory, capable of being properly set and connected without any particular skill, all as will be more fully hereinafter described and claimed.

For a better understanding of the improvements in detail, attention is invited to the accompanying drawings, in which—

Figure 1 is a front elevation of my improved devices, partly in section; Fig. 2, a side elevation with the device for furling and unfurling the sails omitted; Fig. 3, a detail, partly in section, of the stuffing-box and its lower bearing; Fig. 4, a detail in plan of the air-chamber and the bucket or upper bearing for the stuffing-box, and Fig. 5 a section through the air-chamber on the line $x-x$ of Fig. 2.

Like letters of reference denote corresponding parts in the several views.

A denotes a casting, which constitutes the upper guide for the pump-rod a , and in which the two tubes b are secured, preferably by set-screws, so as to be removable, said casting having suitable holes, a' , to receive bolts for securing it to the upright plank A'. (Shown in Fig. 2.)

B is another casting, likewise adapted for attachment to plank A', and which serves as a

lower guide for the pump-rod a and a further support to the tubes b , which pass through it and down through another casting, C, which is screwed or bolted to the platform X of the well, to prevent the parts from becoming loose and having lateral motion.

In the well, a little distance below the platform X, is an air-chamber, D, bolted to a base, D', and provided on top, at diagonally-opposite points, with two ears, c , to receive the tubes b , and further provided between these ears with a separable bearing or bracket, d, which constitutes the upper bearing for a stuffing-box, E, through which passes the pump-rod a down to its head in the pump-cylinder F. This stuffing-box is of tubular form, and is made long enough to extend down to a T-bracket, E', having side flanges, e , bolted to the base D'. The said stuffing-box is screwed into the bracket E', and, by reason of its extraordinary length, strengthens the whole against lateral vibration and insures absolute vertical movement of the pump-rod a . Into the bottom of this bracket is screwed the pipe F', which supports the pump-cylinder F. A tube, f, leads from the bracket E' through the base D' into the bottom of the air-chamber D, where it is covered by a hinged check-valve, f', whereby any water is prevented from returning to the well after entering the air-chamber from this tube. Other tubes, g, lead in opposite directions from the bottom of the air-chamber D, through the base D' into cylinder G and valve-chamber G', which are supported by the base D' upon opposite sides of the air-chamber D.

Within the chamber G' is a ball or any other suitable valve, h, actuated by a rod, h', which extends through the tube b, (screwed into said chamber and into an arm, I, on the upper end,) and is provided on its upper end, which is screw-threaded, with a hand-wheel, h''. By turning this hand-wheel, and thereby depressing this rod, communication is opened between the chamber G' and its tube b, and water is delivered from the pump proper through the tubes f and g, and up through the said tube b to the spout J, which is secured to said tube above its bearing in the casting B. By raising this rod the valve h is returned to its normal position and cuts off the supply of water up through the tube b, and allows the water to be

delivered into a pipe, K, connected to the bottom of the valve-chamber G', which pipe conducts the water up to a tank, L, situated above the ground at any desired distance from the well or spring in which the pump is placed. This pipe K extends into said tank, and has on its upper end a hinged valve, j, controlled by a lever, k, having connections by wire or rope with a float, M, which rises with the water in the tank until the water reaches a certain level, when the short end of the lever k presses down upon the valve j and closes the end of the pipe, so that no more water can flow into the tank. When this action takes place, the pump forces the water into the regulating-cylinder G, which is mounted upon the distributing-base D', and raises its piston N, whose rod N' passes up through the tube b on this side, and is connected at its upper end to a weighted lever, O, which is fulcrumed upon the arm I of the pump-frame above the platform of the well, and to this lever is attached the furling-rod m or n, as the case may require. For instance, the rod m is for connecting the lever with the sails of a wind-wheel in which the rod is to be pushed up to furl the sails, and the rod n is for connecting the lever with the sails of a mill in which the rod is to be pulled down to furl the sails. The pump-rod a may be connected to the windmill in any well-known way. The link p and its handle P are attached to the pump, so that water can be obtained when the mill is not in operation. The operation of my improved pump and regulator is as follows: When the mill is in operation, water is delivered by the pump into the air-chamber, and thence through the several outlets and pipes into the tank above the ground. When the supply to the tank is cut off, the pressure increases in the pipes and the water is forced into the cylinder G, so as to cause the piston N to rise, and likewise the weighted lever O, whereby either the furling-rod m or n is operated to furl the sails of the wheel and thus stop the pump. When the water has been drawn from the tank and the float dropped down to a certain level, water will again commence to flow into the tank, thus relieving the pressure from under the piston, which will then be forced down by the weighted lever and the sails unfurled to the wind. It will be seen that by attaching the regulating-cylinder to the pump-frame below the platform of the well and by fulcruming the weighted lever upon the pump-frame above said platform I have made a very substantial improvement upon the old form of windmill pump and regulator, which, being furnished to the trade in parts or sections, required considerable skill in setting up, and even then it would fail to work satisfactorily on account of imperfect setting of the parts. As it is now, the entire device is complete when it leaves the factory, requiring only to be set in place and connected to the windmill and distributing-pipes.

It will further be seen that by placing the check-valve inside of the air-chamber all water is prevented from returning to the well when the pump is at rest, so as to prevent the unnecessary action of the regulator or the withdrawal of water from the tank.

I do not wish to be confined to a ball-valve for regulating the supply of water up through the tube b, for a three-way cock in the tube 75 just above the base would accomplish the purpose, and in fact there are many such devices which are well known and capable of use for the purpose.

It must be understood that the windmill-regulator is not to be confined to a pump of the construction herein described and illustrated, as it is just as well adapted for use with any other force-pump of this class.

So much of this application as relates to the 85 attachment of the pump-cylinder and connecting parts to the distributing-base I intend to introduce as the subject of a future application on a force-pump, and hence claims to the same are designedly omitted in this application.

I do not broadly claim as my invention the employment of the cylinder and its piston as a windmill-regulator; but

What I do claim as my invention is—

1. A combined force-pump and windmill-regulator provided with a regulating-cylinder attached to and forming a part of the pump-frame, and with a weighted lever fulcrumed directly to the pump-frame, substantially as and for the purposes set forth.

2. The combination, in a force-pump and windmill-regulator, of a regulating-cylinder mounted upon a distributing-base, the cylinder and base forming parts of the pump-frame, a solid piston arranged within said cylinder 105 and having a rod connected with a weighted lever, and a weighted lever fulcrumed directly to the pump-frame, all constructed and arranged substantially as and for the purposes set forth.

3. In a pump of the character described, the combination, with an air-chamber, D, supported below the platform by the tubes b b, of the distributing-base D', regulating-cylinder G, and valve-chamber G', supported by said 115 air-chamber, substantially as and for the purposes set forth.

4. In a pump of the character described, the combination, with an air-chamber, D, supported below the platform by the tubes b b, of the distributing-base D', supported by said air-chamber, and in turn supporting a regulating-cylinder, G, having a solid piston with a rod passing up through one of the tubes b, and connected at its upper end to a weighted lever, O, substantially as and for the purposes set forth.

5. In a pump of the character described, the combination, with an air-chamber, D, supported below the platform by the tubes b b, of the distributing-base D', supported by said air-chamber, and in turn supporting a valve-

chamber, G', into which leads the pipe K from the tank L, substantially as and for the purposes set forth.

6. In a pump of the character described, the combination of the base D', the air-chamber D, the bracket E', the regulating-cylinder G, the valve-chamber G', and the communicating tubes f and g g, substantially as described.

7. The combination, with the main frame, composed of the castings A, B, and C and the tubes b b, of the pump-rod a and cylinder F, the air-chamber D, the base D', the stuffing-

box E, the bracket E', the cylinder G and its piston, the chamber G' and its valve, and the communicating tubes f and g g, all constructed and arranged substantially as described, and for the purposes set forth. 15

In testimony whereof I affix my signature in presence of two witnesses.

GEORGE A. CARTER.
